Primary Examiner—Janice E Seeger*(74) Attorney, Agent, or Firm*—Baker & Daniels LLP(57) CLAIM

The ornamental design for a desk, as shown and described.

DESCRIPTION

FIG. 1 is a front perspective view of a desk of my new design;

FIG. 2 is a front view thereof;

FIG. 3 is a rear view thereof;

FIG. 4 is a left side view thereof;

FIG. 5 is a right side view thereof; and,

FIG. 6 is top view thereof.

The broken lines are for environmental purposes only and form no part of the claimed design.
